SUPPORT MEMBER FOR A CUTTING BOARD OR THE LIKE

Eldon E. Radtke, 5765 Lord Cecil,
San Diego, Calif. 92122

Filed Aug. 16, 1965, Ser. No. 86,601

Term of patent 14 years

(Cl. D44—1)

Fig. 1

The right hand member shown in broken lines in FIGURES 1 and 2 is for illustrative purposes.

I claim:

The ornamental design for a support member for a cutting board or the like, as shown and described.
